Attorneys

UNITED STATES PATENT OFFICE.

JAMES DICKMAN, OF NEW ORLEANS, LOUISIANA, ASSIGNOR OF ONE-HALF TO CAESAR MAESTRI, OF NEW ORLEANS, LOUISIANA.

EXHAUST SILENCER.

Application filed July 31, 1922. Serial No. 578,683.

To all whom it may concern:

Be it known that I, JAMES DICKMAN, a citizen of the United States, residing at New Orleans, in the parish of Orleans and State 5 of Louisiana, have invented new and useful Improvements in Exhaust Silencers, of which the following is a specification.

My present invention pertains to internal combustion engines and it contemplates the 10 provision of a device that may be readily and quickly secured on the exhaust pipe of the engine so as to eliminate the metallic sound or noise of the exhaust.

The invention further contemplates the provision of a device adapted to be secured on the exhaust pipe in such a manner that the gases from the engine are permitted to expand thereby eliminating the annoying sound present in exhaust pipes now in use.

20 Other objects of the invention will be fully understood from the following description and claim when the same are read in connection with the drawings accompanying and forming part of this specification, in 25 which:—

Figure 1 is a side elevation of my device.

Figure 2 is a sectional view taken on the line designated by 2—2 in Figure 1.

Figure 3 is a similar view taken in the 30 plane indicated by the line 3—3 of Figure 1.

Figure 4 is a sectional view taken in the plane indicated by the line 4—4 in Figure 1.

Similar numerals of reference designate 35 corresponding parts in all the views of the drawings.

My novel device comprises the cylindrical portion 1 that is adapted to be secured at its extreme end to the top of the exhaust pipe of an internal combustion engine, and this 40 cylindrical portion 1 merges into a chamber of ball shape which comprises the lower end 5, the central body 3 and the upper or outer end 7 and these members comprising the ball portion are integral with each other as well 45 as the cylindrical portion 1 and are each provided with a series of outlets 4, 6 and 8 respectively. Secured to the upper or outer portion 7 is a cylindrical portion 9 that is similar to the portion 1 with the exception 50 that it is slightly decreased in circumference with respect to the portion 1 and this cylindrical portion 9 is also provided with a series of apertures 10 and is formed integral on the

upper portion 7 of the ball chamber. As will be noted by reference to Figure 2 I provide 55 the central portion 3 of the ball at its upper and lower ends with the wire netting 12 and this netting when desired may be formed of rods or the like in the discretion of the manufacturer.

In order to retain the device on the end of an exhaust pipe I provide a collar that is adapted to surround the decreased cylindrical portion 9 and secured to this collar are cables 11 that may be attached at any point 65 desired to the under side of a motor vehicle or wherever practicable.

In the practical use of the device the exhaust of the engine will pass from the exhaust pipe into my novel device and because 70 of its peculiar configuration as well as the apertures that are provided in the various elements of the silencer, the sound at the outlet will be muffled.

My invention is extremely simple in construction and is readily adapted for use in connection with various sizes or styles of exhaust pipes and may be made of any material compatible with its purpose.

Having described my invention what I 80 claim and desire by Letters Patent is:—

In a device for the purpose set forth, the combination with the exhaust pipe of an internal combustion engine of a comparatively large circular conduit having apertures 85 therein, a large globular portion with apertures therein and formed integral with one end of the large conduit, a foraminous screen secured interiorly of the globular portion and at the center thereof, a comparatively 90 small conduit having apertures and formed integral with the globular portion directly opposite and on the same axis as the large conduit and a collar secured around the small conduit at the longitudinal center thereof 95 and rods extending from the second collar for securing and bracing the entire device with respect to the under side of a motor vehicle.

In testimony whereof I have hereunto set 100 my hand in presence of two subscribing witnesses.

JAMES DICKMAN.

Witnesses:

M. QUANTIN,
CEASAR MAESTRI.
